(57) CLAIM

The ornamental design for a portion of a shoe midsole, as shown and described.

DESCRIPTION

FIG. 1 is a perspective view of a portion of a shoe midsole showing my new design;

FIG. 2 is a side view thereof;

FIG. 3 is a top view of a shoe showing a portion of my new design; and,

FIG. 4 is a rear view of a portion of a shoe midsole showing my new design.

The broken lines showing of the remainder of the shoe are for illustrative purposes only and form no part of the claimed design.
